R. STAEHLE.

SOLDERING TOOL.

APPLICATION FILED JAN. 14, 1910.

979,896.

Patented Dec. 27, 1910.

UNITED STATES PATENT OFFICE.

REINOLD STAEHLE, OF MOUNT VERNON, NEW YORK.

SOLDERING-TOOL.

979,896.

Specification of Letters Patent. Patented Dec. 27, 1910.

Application filed January 14, 1910. Serial No. 538,040.

To all whom it may concern:

Be it known that I, REINOLD STAEHLE, a subject of the Emperor of Germany, residing at Mount Vernon, county of Westchester, 5 State of New York, have invented new and useful Improvements in Soldering-Tools, of which the following is a specification.

This invention relates to improvements in soldering tools of the kind in which the body 10 or the tip portion of the tool is maintained sufficiently hot to remain in working condition.

An object of the invention is to prevent the flame being accidentally extinguished.

15 Suitable means will prevent the handle or tank part from becoming too hot for handling or manipulation.

This invention is set forth in the following specification and claims and illustrated 20 in the annexed drawing in which—

Figure 1 shows a side elevation of a soldering tool embodying this invention. Fig. 2 is a longitudinal central section of Fig. 1. Fig. 3 is a section along the line $x-x$ Fig. 1. 25 Fig. 4 is a section along the line $y-y$ Fig. 1.

In this drawing is shown a reservoir or tank which can also be made to form a handle as indicated at a . The combustible can be of any suitable well known kind such as 30 benzine or the like. The tank a can contain a suitable wick or absorbent b .

An air pump is indicated at c which, when its piston is reciprocated, compresses the air in the tank a and forces the volatile 35 liquid into the wick. The tank can be supplied by a suitable filling opening as indicated at d which can be closed by a screw cap. A screw-cap or nipple e can also be applied at the rear portion back of the 40 pump-stem or tank. From the tank leads an outlet tube f the front part f' of which is suitably shaped to form a valve casing through which the combustible can pass from the outlet tube f . By means of a suitably operated regulating spindle valve i the 45 out-flow of combustible or vapor from the valve casing can be regulated.

The combustible passing off from the burner tip k and suitably consumed in the 50 flame tube m will strike the tip n of the tool to maintain the same suitably heated.

A heating trough o suspended by a suitable bail p from the valve casing f' can be used for starting the heating of the tool.

55 No claim for novelty is made for the parts thus far described.

The outlet tube f is surrounded by a casing q suitably spaced and it can be ventilated by means of openings r so as to prevent excessive heat from being conducted by tube f 60 to the tank a and prevent the latter becoming too hot for manipulation. The casing q is provided with a movable sleeve s which can be slid or adjusted to cover the ventilating openings r to greater or less extent so as 65 to control or regulate the flow of air through the openings r to the tube f .

Heat from the soldering tip end n is conducted by a suitable heat conductor such as a metallic bar t to a connecting piece u and 70 the heat thus conducted will maintain sufficient warmth in the combustible or vapor from the burner tip k so that the flame can be easily maintained in the burner tube m which is shown as provided with ventilating 75 openings or slits. The connecting piece u can be made to straddle the valve casing f' and can be suitably clamped by a screw v . The heat conductor t can be clamped or secured in the connecting piece u by a screw 80 2. The soldering tip is provided with a hood which partly covers it, a portion thereof being shaped to clasp the heat conductor t and one end of the burner tip m . 85

I claim:—

1. A device of the kind described, comprising a tank having a casing projecting therefrom, an outlet tube located in the casing and communicating with the tank, a cooling chamber formed between the casing 90 and the outlet tube, said casing having a series of ventilating passages near the tank and leading to the cooling chamber, and a movable sleeve mounted on the casing adapted to regulate the area of the ventilating 95 passages.

2. A device of the kind described, comprising a tank having an outlet tube, a surrounding spaced casing for the tube provided with ventilating passages, a movable 100 sleeve for regulating the area of the ventilating passages, a valve casing connected to the outlet tube, a soldering tip and a heat conductor connecting the soldering tip to the valve casing. 105

In testimony whereof I have hereunto set my hand in the presence of two subscribing witnesses.

REINOLD STAEHLE.
